BOTTLE OR SIMILAR ARTICLE

Jose Dorelis, New York, N. Y.

Application January 18, 1954, Serial No. 28,567

Term of patent 7 years

(Cl. D58--8)

To all whom it may concern:

Be it known that I, Jose Dorelis, a citizen of the United States of America and resident of the city of New York, county of New York and State of New York, have invented a new, original, and ornamental Design for a Bottle or Similar Article, of which the following is a specification, reference being had to the accompanying drawing, forming part hereof, wherein

Fig. 1 is an elevational view of a bottle, embodying my new design; and

Fig. 2 is a top plan view thereof.

The sides of the bottle not shown are the same as those shown.

I claim:

The ornamental design for a bottle or similar article, substantially as shown and described.
